UNITED STATES PATENT OFFICE.

ADOLF EDWARD MUELLER, OF LOUISVILLE, KENTUCKY.

ADJUSTABLE OVERFLOW ATTACHMENT.

1,262,545.

Specification of Letters Patent.

Patented Apr. 9, 1918.

Application filed January 2, 1918. Serial No. 209,988.

To all whom it may concern:

Be it known that I, ADOLF EDWARD MUELLER, a citizen of the United States, and a resident of Louisville, in the county 5 of Jefferson and State of Kentucky, have invented a new and Improved Adjustable Overflow Attachment, of which the following is a full, clear, and exact description.

This invention relates to an attachment 10 for overflow structures and has for an object the provision of an improved construction adapted for bath tubs, wash basins, and the like, whereby any desired height of water may be secured within certain limits.

15 Another object of the invention is to provide an attachment for an overflow pipe which has an opening and which is rotatable whereby the opening may be positioned at different heights for securing any desired

20 water level.

A still further object of the invention, more specifically, is the provision of an attachment adapted to fit over the usual waste pipe or overflow opening of the bath 25 tub or wash basin and formed with an opening held by a clamping member in any adjusted position, so that the position of the opening will determine the water level regardless of the position of the waste pipe 30 opening.

In the accompanying drawing:—

Figure 1 is a fragmentary view of one end of a bath tub showing an embodiment of the invention applied thereto.

35 Fig. 2 is a section through Fig. 1 on line 2—2.

Fig. 3 is a top plan view of the overflow attachment shown in Fig. 2.

Fig. 4 is a section through Fig. 3 on 40 line 4—4.

Fig. 5 is a view similar to Fig. 1, but showing a slightly modified form of the invention.

Referring to the accompanying drawing 45 by numerals, 1 indicates a bath tub of any desired kind provided with a waste-pipe 2, elbow 3 and a strainer 4 covering the spider 5 integral with the elbow 3. This construction is the usual overflow construction for bath tubs and also for wash basins and the like. Usually there is a screw or other member connected centrally in the strainer 4 to which the stopper chain is secured. In the present instance instead of 50 having the structure just mentioned, a

threaded shaft 6 is screwed into the spider 5 so as to provide a support for a number of other articles. A nut 7 is threaded on to the shaft 6 as shown in Fig. 2 and acts to firmly clamp the strainer 4 in position 60 while a casing or hood 8 surrounds the reduced parts 9 of shaft 6 and rests on the washer 9 and on said reduced part. A hollow boss 10 extends from the outer wall 11 of the hood 8 toward the nut or sleeve 65 7 and contains a spring 12 acting against a flange 13 and against the washer 9, for maintaining the parts in proper position and the edge 14 in contact with the flange 15 of strainer 4. By tightening up the nut 16 70 on the threaded end 17 more or less tension can be provided for the spring 12 for producing any desired pressure of the casing or hood 8 against the flange 15.

It will be observed that the hood or casing 8 is provided with a wall 11 merging to an upstanding flange 18 and also merging into a partially circular wall 20, and the edge 14 of wall 20 has at the upper part an upstanding flange 19 merging into the walls 80 20 and 21. The flanges 18 and 19 are connected by transverse sections 21 and 22 whereby an entrance mouth or passageway is provided which may be positioned at the highest point of the device, as shown in 85 Fig. 1, or at a lower point, as shown in dotted lines in Fig. 1. By this construction and arrangement the water level may be raised from the line 22' (Fig. 1) to line 23, or to any intermediate point. 90

In some instances where the valves and overflow are differently arranged from the showing in Fig. 1, a slightly modified structure is provided in which the casing 8' is provided with an arc shaped tubular member 24 of any desired length. When this form of the invention is used the tubular member 24 is comparatively long so as to extend to near the top of the tub and thereby allow a large quantity of water to be used 100 if desired. An adjustment of either of the devices will allow the use of the minimum amount of water provided by the overflow, or a larger amount as preferred, so as to cover the body more or less when bathing, 105 or for use for other purposes.

What I claim is:

1. In an overflow attachment for tubs, basins, and the like, a hood adapted to fit over the overflow opening, a retaining member 110

- for rotatably supporting said hood, and resilient means for holding said hood in an adjusted position.
2. An overflow attachment for the overflow opening of tubs, basins and the like, comprising a hood adapted to fit over said opening, said hood being formed with an opening in one side, means for rotatably supporting said hood so that said hood may be positioned at any height for varying the height of the water line, and resilient means acting on the hood for producing friction between the hood and the tub whereby the hood is held in any adjusted position.
3. An overflow attachment comprising a hood formed with an open face on one side, an opening on one edge, said last mentioned opening being formed of upwardly extending flanges, and means for clamping the open side of said hood against the tub over the waste discharge opening, said clamping means being formed to permit a rotary movement of the hood so that the second mentioned opening may be positioned at any desired height for varying the water line in the tub.
4. An overflow attachment for tubs comprising a hood having an open side, an inlet on the edge, said hood having a boss extending toward said open side formed hollow and provided with a shoulder, a shaft extending through said boss, a spring arranged in said boss around said shaft and resting on said shoulder, and a nut engaging said shaft, said nut pressing against said spring for maintaining the same at a tension, whereby the hood is resiliently pressed against said tub and held in any adjusted position by the friction created by said pressure.
5. An overflow attachment for tubs and the like comprising a hood adapted to fit over the waste outlet of the tub, said hood being formed with a tubular portion extending an appreciable distance from the main body of the hood at an angle thereto, and means for rotatably clamping said hood in different positions, whereby the opening in the end of said tubular extension may be arranged at different levels.

ADOLF EDWARD MUELLER.
